UNITED STATES PATENT OFFICE.

THOMAS EASTMOORE, OF JACKSONVILLE, FLORIDA, ASSIGNOR OF ONE-HALF TO MATHEW M. FREED, OF JACKSONVILLE, FLORIDA.

ROTARY MOTOR.

SPECIFICATION forming part of Letters Patent No. 756,606, dated April 5, 1904.

Application filed August 21, 1903. Serial No. 170,283. (No model.)

To all whom it may concern:

Be it known that I, THOMAS EASTMOORE, a citizen of the United States, and a resident of Jacksonville, in the county of Duval and State 5 of Florida, have invented a new and Improved Rotary Motor, of which the following is a full, clear, and exact description.

This invention relates to improvements in rotary motors of the turbine type, an object 10 being to provide a rotary motor of simple and durable construction, easily reversed, and arranged to utilize the motive agent to the fullest extent.

Other objects of the invention will appear 15 in the general description.

I will describe a rotary motor embodying my invention and then point out the novel features in the appended claims.

Reference is to be had to the accompanying 20 drawings, forming a part of this specification, in which similar characters of reference indicate corresponding parts in both the figures.

Figure 1 is a side elevation, partly in section, of a rotary motor embodying my invention; and Fig. 2 is a section on the line 22 25 of Fig. 1.

Referring to the drawings, 5 designates the motor-cylinder having annular steam-chambers 6 7 in its heads 8 9. Extended through 30 the cylinder and having bearings in the heads thereof is a shaft 10, on which is mounted the cylindrical piston 11. On this piston 11 is a spirally-disposed rib 12, and in the space between the coils of the rib are metal plates 13, 35 arranged in staggered relation. At the ends, however, I employ three or more plates 14, which are arranged in parallelism and at an obtuse angle with relation to the axis of the cylinder. These several plates are of thin 40 steel or other resilient metal and are secured only at their inner edges, so that said plates may be bent under the influence of the motive-agent pressure. By arranging the plates 13 in staggered relation, or at reverse angles 45 alternately, the steam or other agent will act upon the same as wind upon the sails of a boat.

The object in placing the three or more plates 14 in parallelism at the ends is to pre-

vent the spring of the plates resisting the 50 steam from entering freely at the ends and at the same time giving a greater resistance as the steam leaves the channel of the cylinder.

By providing the annular chambers 6 7 there is a free access and exhaust from all 55 parts of the piston. An inlet-pipe 15, provided with a valve 16, has a branch 17 leading into the chamber 6 and a branch 18 leading into the chamber 7, and at the junction of said branches with the pipe 15 is a two-way 60 valve 19, which may be turned to reverse the direction of rotation of the piston.

The motor is kept in regular movement by means of a governor 20, controlling a valve 65 arranged in the valve-casing 21, the said governor having a miter-pinion 22 engaging with a miter-pinion 23, on the shaft of which is a band-pulley 24, from which a band 25 extends to a band-wheel 26 on the shaft 10.

An exhaust-pipe 27 has a branch connection 70 28 with the steam-chamber 6 and a branch connection 29 with the steam-chamber 7, and at the junction of said pipe 27 with its branches is a reversing-valve 30. On the stem of the valve is an arm 31, from which a link 32 extends to a lever 33, the connection with said lever being above its pivotal point with the standard 34, and from said lever below its pivotal point a link 35 extends to a connection with an arm 36 on the stem of the valve 19. 75 By operating the lever 33 it is obvious that the valve 19 may be rotated to admit steam either to the chamber 6 or the chamber 7, and at the same time the valve 30 will be reversed to permit the exhaust from the proper chamber, 80 and the admission of steam and exhaust may be regulated by moving the valves through the medium of the lever to any desired extent, and the said lever will be held as adjusted by means of a pin 37, carried by said lever and 85 engaging with the rack 38.

In operation, assuming the steam or other motive agent to enter through the chamber 6, the pressure will first be upon the plates 14, which will be bent or deflected, as before mentioned, and pass on through the spiral channel between the ribs, and by this means all 90 the pressure will be utilized, and the said

pressure will operate throughout the entire area of the piston.

Having thus described my invention, I claim as new and desire to secure by Letters Patent—

- 5 1. A rotary motor comprising a cylinder, a cylindrical piston arranged therein, a spirally-disposed rib on the outer surface of said piston, and spring yielding plates arranged in the space between the coils of said rib.
- 10 2. A rotary motor comprising a cylinder, a cylindrical piston arranged therein, a spirally-disposed rib on said piston, and spring yielding plates arranged alternately at reverse angles between the coils of the rib.
- 15 3. A rotary motor comprising a cylinder having annular inlet and exhaust chambers formed in its heads, a rotary piston arranged in the cylinder, yielding plates on the piston, an inlet-pipe having branches communicating with said chambers, means for directing the motive agent through either one of said branches, an exhaust-pipe having branches leading into said chambers, and means for regulating the exhaust.
- 20 4. A rotary motor comprising a cylinder, a cylindrical piston arranged therein, spring

yielding plates on the piston, the heads of said cylinder being provided with annular chambers, motive-agent-supply pipes leading into said chambers, exhaust-pipes leading from said chambers, a valve for controlling the inlet, a valve for controlling the exhaust, and means for simultaneously reversing or operating said valves.

5. A rotary motor comprising a cylinder, a cylindrical piston arranged therein and having a spirally-disposed rib, spring yielding plates arranged in the space between the coils of the rib, the said plates being arranged alternately at reverse angles, and a plurality of 40 spring yielding plates at the ends of the cylinder, the said plates being arranged in parallelism and at an angle with relation to the axis of the piston.

In testimony whereof I have signed my name 45 to this specification in the presence of two subscribing witnesses.

THOMAS EASTMOORE.
